HENRY LEVINE

BY William R. Liberman

ATTORNEY

UNITED STATES PATENT OFFICE

162,551

HOSIERY DISPLAY CONTAINER
OR THE LIKE

Henry Levine, Brooklyn, N. Y.

Application April 25, 1950, Serial No. 9,461

Term of patent 14 years
(Cl. D80—5)To all whom it may concern:

Be it known that I, Henry Levine, a citizen of the United States and a resident of Brooklyn, New York, have invented a new, original, and ornamental Design for Hosiery Display Container or the like, of which the following is a specification, reference being had to the accompanying drawing, forming a part hereof, in which

Figure 1 is an exploded view in perspective of a hosiery display container, or the like, showing my new design;

I claim:

The ornamental design for a hosiery display container, or the like, as shown.
